US00D524788S

(12) **United States Design Patent** (10) **Patent No.:** **US D524,788 S**
(45) **Date of Patent:** **** Jul. 11, 2006**

(54) **CELL PHONE HOUSING**

(76) Inventor: **Thomas R. Beard**, 4444 Moore La., Healdsburg, CA (US) 95448

(**) Term: **14 Years**

(21) Appl. No.: **29/228,117**

(22) Filed: **Apr. 20, 2005**

(51) **LOC (8) Cl.** **14-03**

(52) **U.S. Cl.** **D14/138; D14/143**

(58) **Field of Classification Search** **D14/138, D14/142, 143, 147, 148, 149, 151, 243, 249, D14/251-253; D17/14; D21/405, 517; 455/90.3, 455/556.1, 556.2, 566, 575.1; 379/433.01-433.13, 379/434**

See application file for complete search history.

(57) **CLAIM**

The ornamental design for a cell phone housing, as shown and described.

DESCRIPTION

FIG. 1 is a lower right front perspective view in off mode. FIG. 2 is an upper left rear perspective view in off mode. FIG. 3 is a lower right front perspective view in answer mode.

FIG. 4 is an upper left rear perspective view in answer mode.

FIG. 5 is a front elevational view.

FIG. 6 is a right side elevational view.

FIG. 7 is a rear elevational view.

FIG. 8 is a left side elevational view.

FIG. 9 is a top plan view.

FIG. 10 is a bottom plan view.

FIG. 11 is a lower right front perspective view in open mode; and,

FIG. 12 is an upper left rear perspective view in open mode. The broken line showing of the keypad buttons in FIG. 11 is for illustrative purposes only and forms no part of the claimed design.

1 Claim, 6 Drawing Sheets
